UNITED STATES PATENT OFFICE

ROBERT WATSON, OF CLEVELAND, OHIO, ASSIGNOR TO FIREBAR CORPORATION, OF CLEVELAND, OHIO, A CORPORATION OF DELAWARE

GRATE FRAME

Application filed July 10, 1931. Serial No. 549,845.

This invention relates to grates of the type which comprise frame members and grate bars mounted therein for rocking movement; more specifically, the invention is concerned with a novel frame member for use in a grate for heavy duty purposes, such as in locomotives, boiler furnaces, etc. For purposes of explanation, an embodiment of the invention in a form suitable for installation in locomotives will be illustrated and described in detail but it is to be understood that the utility of the invention is not limited to that particular use.

Locomotive grates as now customarily constructed include a plurality of grate bars of the rocking type, a pair of frame members along the sides of the fire box, and in grates of the larger type, a center frame member, these frame members having sockets for the reception of the trunnions of the grate bars. The frame members are ordinarily made of cast iron in one piece and they extend the entire length of the fire box and consequently may have a length as great as 10 feet. Because of the weight of the grate bars and of the bed of fuel supported thereon, the frame members are necessarily strong and rugged, and it is quite common to make these frame members with a central web and top and bottom flanges, these flanges being as much as 4 inches wide. As a consequence, the grate frame members support a considerable quantity of fuel on their top flanges and in a grate 10 feet long, the total surfaces of the frame members may amount to 6 square feet or more. As the top surfaces of the frame members are ordinarily solid and without openings through them, the fuel supported thereby does not receive adequate air for combustion and its combustion is sluggish and it is not burned completely. The tops of the frame members may consequently be considered dead space, and since the total area of the tops of the frame members may form a substantial proportion of the total grate area, the presence of this dead space reduces the combustion efficiency of the grate to a marked extent.

Grate frame members as heretofore employed have another important objection in

addition to that above mentioned. The tops of these frame members lie in contact with the fuel bed and are consequently raised to a high temperature in service, particularly since they are not cooled by air passing to the fuel. As the members are continuous from one end of the fire box to the other, the expansion throughout the length thereof is cumulative and as the tops of the members in contact with the fuel bed are at a much higher temperature than the bottoms which lie a substantial distance below the fuel bed, the frame members are liable to become warped and distorted in service due to unequal expansion.

My invention is accordingly directed to the provision of grate frame members of a novel construction in which the difficulties above pointed out are overcome. In my new frame members, I provide means extending above the tops of the members and constituting fuel-supporting surfaces, these means conveniently taking the form of fuel-supporting units somewhat similar in construction to grate bar fingers. These units are mounted loosely on the frame members and constitute a top shield which keeps the fuel from contacting with the members. In the new construction, each frame member is provided along its top with a plurality of spaced projections, each projection being shaped to provide a socket for the reception of a grate bar trunnion and mounted on each projection is a fuel-supporting unit. This unit has an opening through it through which the projection extends with the socket exposed so that the weight of the grate bar is taken wholly by the projection and not by the unit. Each unit is also preferably provided with means by which an adequate supply of air for combustion is delivered to the fuel supported thereon and with this arrangement, the tops of the frame members constitute grate surface on which active combustion of the fuel can take place. Also, the units do not transmit heat readily to the frame members so that the expansion difficulties above mentioned are overcome.

For a better understanding of the inven-

tion, reference may be had to the accompanying drawings, in which

Fig. 1 is a view in side elevation showing a portion of a grate frame member constructed in accordance with this invention with one fuel-supporting unit in place thereon;

Fig. 2 is a sectional view through a center and side frame member constructed in accordance with the invention and showing portions of grate bars mounted on said members;

Fig. 3 is a fragmentary elevational view showing a unit in place on a projection, certain parts being shown in section and broken away;

Fig. 4 is a fragmentary plan view of a center frame member showing one unit in position with a grate bar supported on the frame; and

Fig. 5 is a plan view of a fuel-supporting unit employed on the frame member of this invention.

Referring now to Fig. 1, the new frame member comprises a web 10 with a bottom flange 11, the ends of the member being formed to provide a means for mounting the frame member in a suitable support. The web of the frame member may have openings through it, such as that designated 12, to reduce weight and these openings are preferably defined by beads 13 to afford increased strength.

Disposed at intervals along the top of the frame member are projections 14, which are rectangular in section and have walls tapering upward. Each projection has a mounting for the trunnion of a grate bar and for this purpose, the tops of the projections may be channeled as at 15 to provide sockets. At the bottom of each projection, the web is provided with lateral extensions 16 which may be strengthened by ribs 17 extending downwardly therefrom, for example, to a bead 18 defining an opening through the frame member.

Mounted on each projection is a fuel-supporting unit which comprises a body 19 with extensions 20 therefrom. The body has an opening completely through it so that the unit may be mounted loosely on a projection to rest on the lateral extension 16 from the web of the frame member and the tops of the side walls of the body which define the opening are cut away so that that portion of the projection on which the unit is mounted which serves as the trunnion mounting is exposed. In the construction shown in Fig. 3, the channeled top of the projection providing the trunnion socket lies somewhat above the tops of the side walls which define the opening in the unit so that the trunnion 20 rests upon the projection and none of its weight is taken by the unit. The walls of the opening through the unit are tapered to cor-

respond to the taper of the sides of the projection and the unit has a loose fit on the projection so that the unit will not bind against the projection when it is heated. The unit has cut away portions in the lower parts of its walls at 21, 22 for the admission of air to flow upwardly in the space between the walls of the opening and the projection, and these openings also permit ashes to escape in the event that they should enter the space between the projection and the walls of the opening in the unit.

The tops of the extensions 19 from the body of the unit constitute fuel-supporting surface and I prefer to provide these extensions with a plurality of spaced projections 23, the tops of which constitute the supports for the fuel. In the construction illustrated, the side walls of each extension are formed with spaced lugs 24 which provide air passages 25 between them for flow of air upwardly to the fuel carried by the extensions. The projections 23 are arranged in groups of four with the projections of each group separated by generally horizontal air channels 26 and 27 and the groups of units separated by an air channel 28 which extends lengthwise of the extension 19. With this arrangement, air flowing upward through the passages 25 may flow horizontally in the channels 26, 27, 28, cooling the projections and reaching the fuel over a substantial area so that good combustion is attained.

In a side frame member illustrated at 29 in Fig. 2, there is one row of projections 30 while in the center frame member 31, the projections 30 are arranged in pairs, the pairs being disposed at intervals along the frame member. In installing the new frame members, the side frame members and the center frame member are mounted in the fire box in the usual way and the units are then placed on the projections, the center frame member carrying a double row of units from end to end thereof. The units simply rest on the frame member with the tops of the projections exposed, and after each frame member is provided with its quota of units, the grate bars are placed in position. In the construction shown, the grate bars are of the type illustrated in the co-pending application of Buckley, Serial No. 338,352, filed February 8, 1929, although rocking grate bars of other constructions may be mounted in the frame, if desired.

The Buckley bars comprise a carrier 32 having a plurality of fingers 33 and the fingers are of a construction resembling the fuel-supporting units of my grate frames in the respect that these fingers are provided with side lugs and fuel-supporting projections at the tops thereof. The carriers are provided with trunnion arms 34 having trunnions 35 and the carriers are mounted in place with their trunnions resting in sockets 36.

in aligned projections on the center and side frame members. It will be evident that the projections of each pair on the center frame member support the trunnions of a pair of 5 aligned grate bars, which lie on opposite sides of the frame member as shown in Fig. 2.

In order that there may be no break in the 10 grate surface due to the fuel-supporting units on my grate frames, I form the units so that 10 the tops thereof lie substantially in the plane 15 of the fingers or fuel-supporting surfaces of the grate bars with which these frame members are to be employed. If grate bars other than those of the Buckley type are 15 used, some changes in the grate frame units 20 may be necessary but these changes are merely matters of dimension and are within the skill of any mechanic.

While I contemplate that units of other 20 constructions than that described may be employed to advantage, I prefer to provide the units with side lugs defining air channels and with the fuel-supporting projections at their tops because of the wide air distribution 25 thus afforded and because of the excellent results which have been obtained with that type of fuel support in the Buckley grate bar above referred to. Also, I prefer to employ the Buckley grate bar with the new 30 grate frames for the same reasons but it will be apparent that other forms of rocking grate bar may be used with the new frame members if desired.

What I claim is:

35 1. In a grate, a frame member having a plurality of projections along its top, and a fuel-supporting unit mounted loosely on each projection, the top of the projection being exposed through the unit and being shaped 40 to provide a socket for the reception of a grate bar trunnion.

2. In a grate, a frame member having a plurality of projections spaced along its top, and a fuel-supporting unit mounted loosely 45 on each projection, the top of the projection being exposed through the unit and being formed to provide a socket for the trunnion of a grate bar, the bottom of the socket lying above the adjacent portion of the unit where- 50 by the unit provides no support for the trunnion in the socket.

3. In a grate, a frame member having a plurality of projections at its top, and a fuel- 55 supporting unit mounted loosely on each projection, the top of the projection being exposed through the unit and being formed to provide a socket for a grate bar trunnion, the unit having a fuel-supporting surface lying above the top of the projection.

60 4. In a grate, a frame member having a plurality of projections spaced along its top, each projection being formed to provide a socket for the trunnion of a grate bar, and a fuel-supporting unit mounted loosely on each 65 projection and having an opening through

which said projection extends with the socket wholly exposed above the top of the unit, each unit having a fuel-supporting surface and means for supplying air to the fuel carried thereby.

5. In a grate, a frame member having a plurality of projections spaced along its top, each projection having a channel in its top forming a socket for the trunnion of a grate bar, and a fuel-supporting unit mounted on 75 each projection with the socket wholly exposed above the unit, the units of adjacent projections having portions extending toward each other to prevent contact of fuel with the top of the frame member between 80 said projections.

6. In a grate, a frame member having a plurality of projections spaced along its top, each projection being formed to provide a socket for the trunnion of a grate bar, and a fuel-supporting unit mounted loosely on each projection, said unit having an opening through which the projection extends with the socket wholly exposed above said unit, each unit also having a fuel-supporting sur- 90 face with means for supplying air to the fuel carried thereon.

7. In a grate, a frame member having a plurality of projections spaced along its top, each projection being formed with means 95 for supporting the trunnion of a grate bar, and a fuel-supporting unit mounted loosely on each projection, said supporting means being exposed above said unit and said unit having a fuel-supporting surface and a plurality 100 of spaced vertical lugs along its sides below said surface, said lugs between them defining passages for upward flow of air to the fuel on said surface.

8. A grate which comprises the combination 105 of a pair of frame members, each having a plurality of projections spaced along its top, each projection being formed to provide a socket for the trunnion of a grate bar, a fuel-supporting unit mounted loosely on each 110 projection with said socket exposed above said unit, each unit having a fuel-supporting surface, and the surfaces of all of said units on a frame member lying substantially in a plane, and a plurality of grate bars mounted 115 on said frame members, each grate bar having trunnions received in aligned sockets on said members, said grate bar having a fuel-supporting surface substantially in the plane of the fuel-supporting surface provided by said units.

9. A fuel-supporting unit for use on a grate frame, said unit having a body portion having an opening therethrough defined in part by side walls, and extensions from the 125 ends of said body, each extension having a fuel-supporting surface, and the side walls of said opening being cut away at the top to a point substantially below said surfaces.

10. In a grate, a frame member having a 130

plurality of projections arranged in pairs at intervals along its top, each projection being formed to provide a socket for the trunnion of a grate bar, and a fuel-supporting unit 5 mounted loosely on each projection, said unit having an opening therethrough through which said projection extends with its socket exposed above the unit.

11. In a grate, a frame member having a 10 plurality of projections disposed in pairs side by side at intervals along its top, each projection being formed to provide a socket for the trunnion of a grate bar, the grate bars mounted in the projections of the member 15 lying at opposite sides of the frame member, and a fuel-supporting unit mounted loosely on each projection, said projection extending through said unit with its socket lying above the unit.
12. In a grate, a grate frame member having trunnion sockets disposed along it in spaced relation, a plurality of fuel-supporting units mounted on the frame member to shield the top thereof from contact with the 20 fuel on the grate, each unit extending along the member from a point at one side of a trunnion socket to a point on the other side thereof and having an opening through which the portion of the frame member containing the socket extends, and grate bars 25 having trunnions in said sockets and supported wholly thereby.
- 30

In testimony whereof I affix my signature.
ROBERT WATSON.
